(57) **CLAIM**

The ornamental design for a garment fastener with a surface pattern, as shown and described.

DESCRIPTION

FIG. 1 is a front elevational view of a garment fastener with a surface pattern showing my new design; and,

FIG. 2 is a front perspective view.

The dotted line showing of the garment fastener with a surface pattern is for illustrative purposes only and forms no part of the claimed design.

1 Claim, 1 Drawing Sheet

FIG.1

FIG.2
